APPARATUS FOR FEEDING ELASTIC THREAD AT A UNIFORM TENSION

Sterling W. Alderfer, Akron, Ohio, assignor to
The Firestone Tire & Rubber Company, Akron,
Ohio, a corporation of Ohio

Application October 14, 1940, Serial No. 361,048

4 Claims. (Cl. 66—132)

This invention relates to elastic thread, and more especially to method and apparatus for feeding elastic thread at a uniform tension.

At the present time, all circular knitting machines utilize the knitting needles to draw the amount of thread into the machine which is required to make the particular stretch desired in the fabricated article. Variations in the length or degree of stretch desired are adjusted by varying the motion of the knitting needles. When elastic thread, such as rubber thread, or covered rubber thread is knitted, the same practice is followed except that the thread is fed through a tension device before it is fed to the knitting needles. The amount of elastic thread fed into the machine then is governed not only by the knitting needles but also by an extra factor applied to the thread through the tension device.

The present invention, broadly speaking, is to provide methods and apparatus for feeding elastic thread to a knitting machine and controlling the constant speed (uniform tension) delivery of the thread from the spool or package on which the elastic thread is stored. This differs from prior thread feeding devices in that the knitting needles themselves do not determine the amount of thread fed to the knitting machine.

The general object of the present invention, therefore, is to provide a novel and improved method of feeding elastic yarn at a constant rate to a desired point, such as a knitting machine.

A further object of the invention is to provide uncomplicated, inexpensive apparatus for positively feeding uniformly-tensioned rubber thread at a uniform rate to a desired fabricating device.

The above and further objects will be manifest from the following specification, which will be described with particular reference to the accompanying drawings, in which:

Figure 1 is an elevation of apparatus embodying the invention;

Figure 2 is a side elevation of the apparatus shown in Figure 1; and

Figure 3 is an elevation of a modified type of drive means for use in practicing the invention.

Referring to the specific parts shown in the drawing, a frame 10 is provided that supports a motor 11 that in turn drives a shaft 12. This motor 11 also drives a circular knitting head 13 that is carried by the frame 10 for rotation thereon. A large sprocket gear 14, secured on a shaft 15 that is journaled on the frame 10, is driven from the shaft 12 through gear 16 engaging with the sprocket gear 14.

Elastic thread 17 to be fed to the fabricating

head 13 is carried on a spool 18 having flanges 19 at the edges thereof with the spool 18 being supported on a cylindrical roll 21. This roll 21 is carried on a shaft 22 that is journaled in vertically directed arms 23 that are secured to a bracket 24 carried on a rod 25 that is affixed to the frame 10. Two arms 23 are provided on the bracket 24, being positioned at opposite edges thereof, and the upper ends of the arms 23 have slots 26 formed therein. A shaft 27 extends through the spool 18 and the ends thereof are confined in the slots 26 whereby the spool 18 is permitted to move up and down in a vertical plane but is held against other movement, whereby the spool 18 can be rotated while positioned by the arms 23. A constant speed drive is provided for the roll 21 whereby a constant surface rotational speed is given to the spool 18 and the thread 17 is unrolled therefrom at a uniform rate. The thread 17 must be wound upon the spool 18 under uniform tension. The roller 21 is driven by a belt 28 that extends between a conical roll 29 carried on the shaft 22 and a conical roll 31 which is carried on the shaft 32 that is journaled on arms 33 carried by the frame 10 adjacent the sprocket gear 14. A small spur gear 34 is also carried by the shaft 32 and it engages with the gear 14 to be positively driven thereby. Note that the conical rollers 29 and 31 have opposite directions of taper whereby the speed at which the roll 29 can be driven can be varied by changing the position of the belt 28 relative to the driving roll 31 and the driven roll 29. A belt positioning yoke 35 is supported on the rod 25 through a bar 36 with the yoke 35 being movable along the bar 36 whereby the yoke 35 can be placed in any desired position and then retained in such position. This maintains the belt 28 in its given position, since the belt passes through the yoke and its position is limited thereby.

Removal of the thread 17 from the spool 18 is facilitated by means of positively driven pinch rolls 37 and 37a between which the elastic thread is drawn. These rolls 37 are driven by a chain 38 that extends between a sprocket 39 carried on the driven shaft 22 and a sprocket 41 on the shaft 42 mounting the roller 37. Note that the sprocket 39 is larger than the sprocket 41 whereby the pinch rolls 37 and 37a are rotated faster than the shaft 22. Then, too, the diameters of the rolls 37 and 37a are substantially the same as the roller 21 whereby the surface speed of the rolls 37 and 37a is faster than the surface speed of roller 21. Hence rolls 37 and 37a set up addi-

tional tension on the thread 17 unwrapped from the spool 18. The thread 17 goes directly to the knitting head 13 from the pinch rollers 31 and 31a. Ordinarily, the knitting head 13 requires a shorter length of thread than that length 5 of thread, as tensioned, which the pinch rollers pull from the spool 18. Hence, the thread 17 may relax appreciably between the pinch rollers and the knitting head.

The pinch rollers 31 and 31a function to draw 10 the elastic thread positively from the roll 18 and prevent the thread from sticking or catching on the spool. Note that the feed of the thread from the spool 18 is constant and is determined solely by the speed at which the roll 21 is driven.

Figure 3 shows a modification of the belt driving means positioned between the conical drive rolls 29 and 31 of Figures 1 and 2. In this instance a belt 28a is compressed between rolls 29a and 31a and merely looped loosely around the lower drive roll. An arcuate guide sleeve 51 is provided which positions the belt 28a and leads it into a predetermined position between the drive rollers. This arcuate guide 51 is retained in position by spring 52 that is mounted 20 on a support 53 carried by and transversely adjustable on a rod 54.

In view of the foregoing it will be seen that an inexpensive apparatus and method for feeding elastic thread at a uniform rate has been 30 provided and the objects of the invention have been realized.

It will be appreciated that the foregoing description of the invention is for illustrative purposes only and that the scope of the invention 35 includes modifications thereof such as come under the appended claims.

What is claimed is:

1. Apparatus for feeding elastic thread comprising a spool having elastic thread thereon, roller means for supporting said spool directly on

the thread carrying surface thereof, means for retaining said spool on said roller means, a circular knitting head, means for driving said circular knitting head, said means being connected to drive said roller means, pinch rolls between which the thread passes in going from said spool to said knitting head, and means connecting said pinch rolls to said roller means whereby said pinch rolls are rotated faster than the surface speed of said roller means and said thread is tensioned and pulled from said spool by said pinch rolls.

2. Apparatus for feeding elastic thread comprising a spool having uniformly tensioned elastic thread wrapped therearound, roller means for supporting said spool directly on the thread carrying surface thereof, means for retaining said spool on said roller means, means for driving said roller means, pinch rolls between which the thread passes, and means connecting said pinch rolls to said roller means whereby said pinch rolls are rotated faster than the surface speed of said roller means and said thread is tensioned and pulled from said spool by said pinch rolls.

3. In apparatus for feeding elastic thread at a constant rate, the combination of a spool having uniformly tensioned elastic thread on the surface thereof, means for rotating the outer periphery of the thread covering on said spool at a uniform rate to unroll thread therefrom, and means for uniformly increasing the tension of the thread as it is drawn from said spool at a uniform rate.

4. Apparatus as in claim 3 wherein the elastic thread is fed to a knitting head and the means for drawing the thread from the spool prevents transfer of any tension in the elastic thread produced by said knitting head to the thread on the spool.

STERLING W. ALDERFER.
